UNITED STATES PATENT OFFICE.

CYRUS L. BUNDY, OF EAST ORANGE, NEW JERSEY, ASSIGNOR OF ONE-HALF TO WILLIAM BOHLEBER, OF NEW YORK, N. Y.; WILLIAM BOHLEBER EXECUTOR OF SAID CYRUS L. BUNDY, DECEASED.

SPARK-PLUG.

1,300,569.

Specification of Letters Patent. Patented Apr. 15, 1919.

Application filed November 2, 1915. Serial No. 59,170.

To all whom it may concern:

Be it known that I, CYRUS L. BUNDY, a citizen of the United States, residing at East Orange, in the county of Essex and State of New Jersey, have invented certain new and useful Improvements in Spark-Plugs, of which the following is a full, clear, and exact description.

The invention which constitutes the subject matter of this application relates to a spark plug, and particularly to that type of plug which has a removable core.

Referring to the drawings:

Figure 1 is a full sized side view of a spark plug showing one of the preferred embodiments of my invention.

Fig. 2 is a central vertical section showing the position of the parts when the core is held in operative or normal position.

Fig. 3 shows the position of the parts when the lock nut has been partially unscrewed from the bushing.

Fig. 4 shows a section taken on the line 4-4 of Fig. 1, the full and dotted lines illustrating the different angles at which the wrench handle may be inserted into the lock-nut.

Fig. 5 is a cross sectional view of another preferred embodiment of my invention.

Fig. 6 is a section taken on line 6-6 of Fig. 5.

Fig. 7 illustrates a detail employed with the modified form shown in Figs. 5 and 6, and equally capable of use with the form of invention shown in Figs. 1 to 4 inclusive.

Fig. 8 shows a further modification particularly designed to have the handle permanently attached thereto.

Fig. 9 is a top plan view of form shown in Fig. 8.

Fig. 10 is a side view of a still further modification of the invention.

Fig. 11 is a top plan view of the modification shown in Fig. 10.

Referring first to Figs. 1 to 4 inclusive, the reference numeral 10 designates the bushing, 11 the core or insulator, and 12 and 13 the electrodes of the spark plug all of which are

of known construction except in the particulars hereafter mentioned.

The bushing 10 is provided with the usual shoulder 14 which corresponds with the shoulder 15 on the core 11. The bushing 10 is also provided with an interior screw-thread 16 adapted to receive the screw-threads 17 on the lock-nut 18, while the said lock-nut 18 is provided with a plurality of lateral perforations 19 to receive the bifurcations 20 of the handle or wrench 21. A metallic or other washer 22 may be provided, if desired, upon the upper shoulder 23 of the core, and a suitable gasket may be interposed between the shoulder 14 on the bushing and the shoulder 15 on the core to effect a fluid tight connection at this point.

The operation, as regards Figs. 1 to 4 inclusive, is as follows: The bushing 10 is first set in the engine in the usual way as with other types of spark plugs. The core 11 is next inserted within the bushing and then the lock-nut 18 screwthreaded to the bushing 10, as shown in Fig. 3. Or since the interior diameter of the bushing 18 is slightly greater than the greatest diameter of core, it would be equally feasible to screwthread the lock-nut to the bushing before the core is placed thereon. However this is a matter of taste.

The bifurcation 20 of the handle 21 is then projected laterally through the perforations 19, as shown, for instance, in the full lines 80 of Fig. 4, it being of course understood that in the particular construction shown the handle could be inserted from three other directions, as shown in dotted lines. The position of the parts at this point is that clearly 85 shown in Fig. 3. If the handle is now given a turning movement in the proper direction, depending, of course, upon whether a right or left hand screw-thread is used, the lock-nut 18 will be moved toward the core and

cause the bifurcations to engage the washer 22, as shown in Fig. 2. Any further movement after engagement will result in a forcing or tightening action between the shoulders of the core and bushing. So long 95 as the core is loose and in the position shown

in Fig. 3 the handle 21 is free to be withdrawn laterally from the perforations 19, but when in normal operative position, as shown in Fig. 2, it cannot fall out as it is held therein by the upward pressure of the core and the downward pressure of the bushing. In the construction shown the handle 21 may be placed in any one of four positions (see Fig. 4) and should there be any obstructions preventing its complete rotation the handle may be moved as far as it will go, withdrawn from the lateral perforations, and moved backwardly to a succeeding position. In this way the handle may be given at least a quarter turn at each operation, and this operation repeated until the bifurcations 20 of the handle 21 engage with the top of the core or the metallic washer placed thereon. After this engagement only a slight movement of the handle is required to effect a fluid tight connection between the shoulders 14 and 15. The upward pressure on the bifurcations by their engagement with the core causes said bifurcations to bind against the upper walls of the lateral perforations and the upper surface of the metallic washer 22, and the tighter the lock-nut is screwed down the tighter this binding engagement becomes. To remove the core it is only necessary to reverse the handle slightly, say from one-thirty-second to one-eighth of a turn, when the binding engagement referred to is broken and the handle may be withdrawn laterally from the perforations 19, leaving the core free to be withdrawn from the bushing.

From the above it will be seen that I have constructed a spark plug of the removable core type which not only contains a small number of parts, but is cheap to manufacture and positive in operation. The removability of the core not only enables the engine to be primed through the spark plug, but also gives accessibility to the electrodes without the necessity of removing the bushing from the engine, the electrodes being carried by the core as shown. Another important advantage of my device resides in the fact that should the porcelain core or other electric insulator break or otherwise become useless a new core or insulator can be purchased without the necessity of purchasing a new plug as an entirety.

One of the more important features of my invention consists in providing a spark plug of this type with a means for moving the lock-nut downward by means of a step-by-step movement similar to the movement by means of a pawl and ratchet, at the same time causing an engagement of said means with the core to effect a fluid tight union between the latter and the bushing. In other words, I employ means for imparting

rotative impulses to said lock-nut, said means also being adapted to engage the upper end of the core to effect a fluid tight joint between the bushing and the core. This is desirable because, among other reasons, most gas engines, and especially those used on automobiles, are provided with mechanical obstructions adjacent the spark plug which makes it impossible to impart a complete rotation to the handle 21.

Referring to Figs. 5 to 7 inclusive, the bushing 10 and lock-nut 18 differ from the form shown in Figs. 1 to 4 in having the cooperating screwthreads reversed; that is to say, the bushing is externally screw-threaded and the lock-nut is internally screw-threaded. Interposed however between the bifurcations 20 of the handle and the upper shoulder of the core 11 is a grooved washer 24, the groove 25 thereof (see Fig. 7) being defined by the upper and lower flanges 26 and 27, the former of which is of greater diameter than the latter and is preferably adapted to rest upon the shoulder 28 of the lock-nut 18. By resting the washer 24 upon the shoulder 28 the groove 25 is always in alinement with the perforations 19 of the lock-nut 18. The grooved washer may be cemented or otherwise directly connected to the core and serves, not only as a bearing for the bifurcations 20, but also to exclude foreign matter from the interior of the plug. It will be understood that the grooved washer 25 is equally adapted to be used in connection with the form of my invention shown in Figs. 1 to 4 inclusive.

The preferred forms of my invention are shown in Figs. 1 to 7 inclusive. However I illustrate in Figs. 8 to 11 inclusive two further modifications, and these I will now proceed to describe.

Referring to Figs. 8 and 9, the parts are the same excepting the lock-nut 18^a and handle 21^a. The former is a sleeve provided with a "hex" flange 29 upon the upper end thereof. The handle has a substantially circular opening 30 and a slot 31 radiating from said circular opening. The handle is also provided with a stop 32 for limiting its movement in one direction and a turnover flange 33 for not only limiting its movement in the other direction, but also to turn the lock-nut 18^a in either direction. When in the position shown in Fig. 9 the upper portion of the core lies between the sides of the slot 26, the handle in this position bearing directly upon the upper shoulder of the core. When in the dotted line position, with the lug 33 bearing against the lock-nut, the perforation 30 registers with the perforation in the core, and the latter can then be withdrawn through said handle. It will therefore be seen that I have provided a laterally

movable means secured to the lock-nut to rotate the same, which means comprises a handle having an elongated opening therein through which the upper portion of the core projects. This elongated opening is enlarged at one end to permit the withdrawal of the core and is reduced at its other end so that the surrounding metal of the handle is adapted to engage and disengage with the upper shoulder of the core upon the rotation of the lock-nut.

In Figs. 10 and 11 I illustrate a further modification, in which the lock-nut 18^b is provided with arms or ears 34 which extend upwardly from the lock-nut and overhang the bifurcations 20 of the handle 21. The lock-nut in this instance is preferably hexagon shaped. The overhanging flanges 35 constitute engaging surfaces for the bifurcations 20 of the member 21. It will be understood that the bifurcated member is adapted to be moved laterally under said engaging surface, and is adapted to engage the core upon the rotation of said member to effect a fluid tight joint between the core and bushing.

It is to be understood that I do not limit myself to the exact construction shown and described, as many changes can be obviously made in point of detail and other modifications resorted to without necessarily departing from the true spirit and scope of my invention.

What I claim is:

35 1. In a spark plug, a bushing provided
with a screw thread at its upper end and an
annular shoulder at an intermediate point, a
removable core for said bushing provided
with a shoulder normally resting upon the
40 shoulder of the bushing, and means for
removably securing said core to the bush-
ing, comprising a hollow lock nut through
which the core may be inserted and with-
drawn and provided with a plurality of
45 lateral perforations therein, in combina-
tion with means provided with a portion
adapted to pass laterally through said per-
forations and engage with said core for mov-
ing the lock nut downward to effect a fluid
50 tight union between the core and bushing.

2. In a spark plug, a bushing provided with a screw thread at its upper end and an annular shoulder at an intermediate point, a removable core for said bushing provided
55 with a shoulder normally resting upon the shoulder of the bushing, and means for removably securing said core to the bushing, comprising a hollow lock nut through which the core may be inserted and withdrawn and
60 provided with a plurality of lateral perforations therein, in combination with means adapted to be laterally inserted into and withdrawn from said perforations to impart

a step-by-step movement to said lock nut, said means also adapted to engage said core for affecting a fluid tight union between the core and bushing and said engagement rendering the said means rigid with the plug. **65**

3. In a spark plug, a bushing provided with a screw thread at its upper end and an annular shoulder at an intermediate point, a removable core for said bushing provided with a shoulder normally resting upon the shoulder of the bushing, and means for removably securing said core to the bushing, comprising a hollow lock-nut through which the core may be inserted and withdrawn and provided with a plurality of lateral perforations therein, in combination with means, provided with a portion adapted to pass through said lateral perforations and engage with said core, for moving the lock-nut downward to effect a fluid tight union between the core and bushing. 70 75 80

4. In a spark plug, a bushing provided 85
with a screw thread at its upper end and an
annular shoulder at an intermediate point,
a removable core for said bushing provided
with a shoulder normally resting upon the
shoulder of the bushing, and means for re- 90
movably securing said core to the bushing,
comprising a hollow lock-nut through which
the core may be inserted and withdrawn and
provided with a plurality of lateral perfor- 95
ations therein in combination with means
adapted to be inserted into and withdrawn
laterally from said perforations to impart
a step-by-step movement to said lock-nut,
said means also adapted to engage said core 100
for effecting a fluid tight union between the
core and bushing and said engagement ren-
dering the said means rigid with plug.

5. In a spark plug, a bushing provided with a screw thread at its upper end and an annular shoulder at an intermediate point, 105 a removable core for said bushing provided with a shoulder normally resting upon the shoulder of the bushing, and a hollow lock-nut screw-threaded to said bushing through which the core may be inserted and withdrawn and provided with lateral perforations therein, in combination with means for rotating said lock-nut and effecting a fluid-tight joint between the core and bushing, comprising a removable member adapted to 110 be inserted into and removed laterally from said perforations, said member adapted to engage and disengage said core upon the rotation thereof. 115

6. In a spark plug, a bushing provided 120 with a screw thread at its upper end, a removable core for said bushing, a hollow lock-nut screw-threaded to the bushing and provided with a plurality of lateral perforations therein in combination with means 125 for imparting a step-by-step rotative move-

- ment to said lock-nut, and for effecting a fluid-tight joint between the core and bushing comprising a handle or wrench, one end of which is adapted to pass through said 6 perforations from a plurality of positions and engage with the core.
7. In a spark plug, a bushing provided with a screw-thread at its upper end, a removable core for said bushing, a hollow lock-nut provided with a screw thread engaging with the screw thread on the bushing and also provided with lateral perforations therein, in combination with means adapted to impart a step-by-step impulse to said lock-nut to effect a fluid-tight joint between the core and bushing comprising a handle or wrench, one end of which is adapted to pass through said perforations from a plurality of directions and engage with the core, the other end of said handle constituting means for rotating said lock-nut.
8. In a spark plug, a bushing, a removable core for said bushing, a hollow rotatable lock-nut screw-threaded to the bushing and provided with a plurality of lateral perforations therein, in combination with a means for rotating said lock-nut to effect a fluid-tight connection between the core and bushing, comprising a handle, one end of which is capable of being inserted into and withdrawn from said perforations to effect a step-by-step movement to said lock-nut and said end also adapted to engage with the core to effect said fluid-tight connection.
9. In a spark plug, a bushing, a removable core for said bushing, a hollow rotatable lock-nut screw-threaded to the bushing and provided with a plurality of lateral perforations therein, in combination with a member for imparting rotative impulses to said lock-nut, one end of said member adapted to pass through said perforations from a plurality of directions and to engage the core, and the other end of which constitutes a handle or lever for imparting said impulses to effect a fluid-tight connection between the shoulders of the core and bushing.
10. In a spark plug, a bushing, a removable core for said bushing, a hollow rotatable lock-nut screw-threaded to the bushing and provided with a plurality of lateral perforations therein, in combination with a member for rotating said lock-nut, said member having a portion passing through said perforations and adapted to engage said core upon the rotation of said member to effect a fluid-tight connection between said core and bushing.
11. In a spark plug, a bushing, a removable core for said bushing, a hollow rotatable lock-nut screw-threaded to the bushing and provided with a plurality of lateral perforations therein, in combination with a member for rotating said lock-nut, said member having a portion adapted to pass through said perforations and to engage with the core to effect a fluid-tight joint between the core and bushing comprising a handle or wrench, one end of which is adapted to pass through said perforations from a plurality of positions and engage with the core.
12. In a spark plug, a bushing, a removable core for said bushing, a hollow rotatable lock-nut screw-threaded to the bushing, in combination with a member adapted to rotate the same, said member having a bifurcated portion for straddling the upper portion of the core and adapted to engage with the core and lock-nut to effect a fluid-tight connection between said core and bushing upon the rotation of said member.
13. In a spark plug, a bushing, a removable core for said bushing, a hollow rotatable lock-nut screw-threaded to the bushing and provided with a plurality of lateral perforations therein, in combination with a member adapted to rotate the same, said member having a bifurcated portion which passes laterally through said perforations, and straddles and engages the upper portion of the core.
14. In a spark plug, a bushing, a removable core for said bushing, a hollow rotatable lock-nut screw-threaded to the bushing and provided with a plurality of lateral perforations therein, in combination with a member adapted to impart rotative impulses to said lock-nut, said member having a bifurcated portion adapted to enter said lateral perforations from a plurality of directions and to straddle and engage the upper portion of the core, said member also having a handle or wrench portion connected to said bifurcated portion.
15. In a spark plug, a bushing, a removable core for said bushing, a hollow rotatable lock-nut screw-threaded to the bushing and provided with a plurality of lateral perforations therein, in combination with means for imparting rotative impulses to said lock-nut and to engage with the upper end of said core to effect a fluid-tight joint between the core and bushing comprising a member having a bifurcated portion adapted to enter said lateral perforations from a plurality of directions and straddle the core, and also having a portion which acts as a lever to effect said impulses.
16. In a spark plug, a bushing, a removable core for said bushing, a hollow rotatable lock-nut screw-threaded to the bushing and provided with a plurality of lateral perforations therein, in combination with

- means for imparting rotative impulses to said lock-nut and to engage with the upper end of said core to effect a fluid-tight joint between the core and bushing comprising a member having a portion adapted to enter said lateral perforations from a plurality of directions, and also having a portion which acts as a lever to effect said impulses.
17. In a spark plug, a bushing; a removable core for said bushing provided with an upper shoulder, a hollow rotatable lock-nut screw-threaded to the bushing and provided with a plurality of lateral perforations therein, a washer within said bushing provided with an annular groove and adapted to rest upon the upper shoulder on the core, in combination with a member for imparting rotative impulses to said lock-nut, said member having a portion adapted to pass through said lateral perforations and the groove from a plurality of directions.
18. In a spark plug, a bushing, a removable core for said bushing provided with a shoulder at the upper end thereof, a hollow rotatable lock-nut screw-threaded to the bushing and provided with a plurality of lateral perforations therein, in combination with a member for imparting rotative impulses to said lock-nut to make a tight joint between the core and bushing, said member having a portion adapted to pass through said lateral perforations from a plurality of directions and engage with the upper shoulder of the core.
19. In a spark plug, the combination of a relatively fixed member; an electrode carrying insulator adapted to removably seat therein; and an element rotatable about the longitudinal axis of the insulator and removable, by movement in a plane transverse to the axis of the insulator, and adapted when rotated to apply pressure to the insulator in the direction of its axis to lock the insulator to its seat.
20. In a spark plug, the combination of a relatively fixed member; an electrode carrying insulator adapted to removably seat therein; and an element, provided with an operating handle by which said element rotated about the longitudinal axis of the insulator and may be removed by movement in a plane transverse to the axis of the insulator and adapted when rotated to apply pressure to the insulator in the direction of its axis to lock the insulator to its seat.
21. In a spark plug, the combination of a relatively fixed member; an electrode carrying insulator adapted to removably seat therein; and an element rotatable about the longitudinal axis of the insulator and removable by movement in a plane transverse to the axis of the insulator and extending over a portion of the insulator, said element being adapted when rotated to apply pressure to the insulator in the direction of its axis to lock the insulator to its seat.
22. In a spark plug, the combination of a relatively fixed member; an electrode carrying insulator adapted to removably seat therein; and an element rotatable about the longitudinal axis of the insulator and fulcruming on a bearing surface and acting on said insulator to apply pressure to force it to its seat, provision being made whereby the distance of said bearing surface from said seat may be varied by the rotation of said element.
23. In a spark plug, the combination of a relatively fixed member, an electrode carrying insulator adapted to removably seat therein and an element rotatable about the longitudinal axis of the insulator and fulcruming on a bearing surface and extending over a portion of the insulator, said element adapted to be rotated about said axis to apply pressure to said insulator to force it to its seat, provision being made whereby the distance of said bearing surface from said seat may be varied.
24. In a spark plug, the combination of a relatively fixed member, an electrode carrying insulator adapted to removably seat therein, an element rotatable about the longitudinal axis of the insulator and removable by movement in a plane transverse to the axis of the insulator, and adapted when actuated to apply pressure to the insulator in the direction of its axis to lock the insulator to its seat, and an intermediate member transmitting pressure from said element to said insulator.
25. In a spark plug, the combination of a relatively fixed member, an electrode carrying insulator adapted to removably seat therein, an element, rotatable about the longitudinal axis of the insulator and provided with an operating handle by which said element may be removed by movement in a plane transverse to the axis of the insulator and by which said element may be actuated so as to apply pressure to the insulator in the direction of its axis to lock the insulator to its seat, and an intermediate member transmitting pressure from said element to said insulator.
26. In a spark plug, the combination of a relatively fixed member, an electrode carrying insulator adapted to removably seat therein, an element, rotatable about the longitudinal axis of the insulator and removable by movement in a plane transversely to the axis of the insulator and extending over a portion of the insulator, said element being adapted when rotated to apply pressure to the insulator in the direction of its axis to lock the insulator to its seat.

seat, and an intermediate member transmitting pressure from said element to said insulator.

27. In a spark plug, the combination of a 5 relatively fixed member, an electrode carrying insulator adapted to removably seat therein, and provided with an upwardly-facing shoulder, an element rotatable about the longitudinal axis of the insulator and 10 removable by movement in a plane trans-

verse to the axis of the insulator and adapted to be actuated to apply pressure to the insulator in the direction of its axis to lock it to its seat, and an intermediate member acting on said shoulder of the insulator and 15 transmitting pressure thereto from said element.

In testimony whereof I affix my signature.

CYRUS L. BUNDY.
